COMBINED SEAL AND BAG EMPTYING DEVICE

Herbert T. Luna and William W. Fox, Van Nuys, Calif., assignors, by direct and mesne assignments, of one-fourth to George A. Sherman, one-fourth to Herbert T. Luna, one-fourth to William W. Fox, all of Van Nuys, and one-fourth to Jack E. Guyer, North Hollywood, Calif.

Application July 22, 1953, Serial No. 369,636

11 Claims. (Cl. 214—302)

This invention relates to hopper devices and more particularly to a hopper device for use with a plaster mixing machine for sealing the mixing chamber thereof.

Present day plaster mixing machines comprise a tank forming a chamber in which the constituents making up the plaster are thoroughly intermixed. The intermixing usually is accomplished through a series of paddle-like members which are rotatably driven through the plaster mix held by the chamber formed by the tank. Such machines have been used over a long period of time and the constituents of the plaster are introduced into an opening formed into an upper wall of the tank and discharged, after the mixing operation, through a discharge chute leading from the same opening.

In actual use a workman fills the tank from the one side of the machine and discharges the finished plaster from the opposite side of the machine by rotating the tank to discharge the mixed plaster into the chute for reception in a receiving container. Heretofore this opening has not been covered, for the constituents used to form the plaster have been sufficiently heavy to stay within the tank once they are placed therein.

Under present day practices many light weight filler materials such as expanded mica are being used and these light weight filler materials are difficult to intermix with the other constituents of the plaster. They are so light in weight that they tend to rise out of the mixer not only during the filling operation, but also during the initial stages of the mixing operation. The portion of these materials which escape from the mixer not only increases the cleanup operations around the mixer, but also are exceedingly irritating to the eyes, lungs, and skins of the plasterers working about the mixer.

The device of the present invention obviates the difficulties heretofore experienced with these light weight filler materials for although it permits their use it prevents escape of these materials not only during the operation of introducing the materials into the mixer, but also during the mixing operation as well.

The device of the present invention in its broadest aspects comprises a cover element including a stationary section to be fixed to the tank and a pair of sections hingedly mounted to opposite sides of the stationary section. The hingedly mounted sections, when the cover element is mounted to the tank of the mixer, are operative to cover the filling and discharge portions of the opening. The cover element is of such a size as to completely seal the opening in the tank and although heavier materials can be introduced into the tank by moving the one hingedly mounted section to uncover a portion of the opening, the light weight materials are introduced through a hopper carried by the cover element. The hopper is formed with flared walls to facilitate reception of the one end portion of the bag containing the light weight filler material and these walls coact with the bag to prevent escape of the light weight material upwardly of the hopper as the material is discharged from the bag.

To permit discharge of the light weight material from the bag in which it is furnished, the present invention provides a plurality of cutter elements spacially mounted across the discharge opening of the hopper which, when operated, rupture the end portion of the bag received within the hopper to permit the contents thereof to dis-

2

charge into the tank. As the bag acts to seal the hopper and as the cover element completely closes the opening in the tank, the light weight material is prevented from escaping into the atmosphere during the mixing operation. Once the light weight filler material is thoroughly intermixed with the water and other constituents of the plaster, it is held by the mix itself from escaping into the atmosphere. The plaster, after the mixing operation, can be discharged from the tank by moving the hingedly mounted section of the cover element closing the discharge portion of the tank opening to its open position and rocking the tank to permit discharge of the plaster.

To facilitate the introduction of the light weight material from the bag into the tank, the hopper includes a support element carrying a plurality of sharpened elements on which the bag may be supported by thrusting the bag against the elements to cause the same to pierce the bag. The bag is thereafter partially supported by the sharpened elements and as these elements actually puncture the bag wall they permit ingress of air into the bag as the contents thereof are discharged through the hopper into the tank.

Although the cover element includes means for attaching the same to the tank, it can be removed by disengaging the attaching means used to permit cleaning of the device if found necessary. The cover element is easily attached to an existing plaster mixing machine and the mounting operation does not require any extensive modification of the existing machine.

Other features and advantages of the present invention will be hereinafter apparent from the following description, particularly when taken in connection with the accompanying drawing, in which

Figure 1 is a perspective view showing the combined seal and hopper member mounted to the tank of a plaster mixing machine;

Figure 2 is a section taken along line 2—2 of Figure 1;

Figure 3 is a perspective view of the bag rupturing means removed from the device; and

Figure 4 is a section taken along line 4—4 of Figure 1.

The hopper device of the present invention, referring now to the drawing and more particularly to Figure 1 thereof, comprises a cover element 10 formed of three sections 11, 12, and 13, the adjacent marginal edges of which are pivotally interconnected preferably by continuous hinges 14. The cover element 10 is to be mounted to a plaster mixing machine of which only the mixing tank 15 has been illustrated in the drawing. This mixing tank, as illustrated in the drawing, comprises a somewhat cylindrical body portion having upwardly flared walls 16 and 17 forming a relatively large opening at the normal upper side of the tank. This opening is used to both fill the tank and to discharge the plaster from the tank. In practically all of the plaster mixing machines in use today the portion of the opening defined in part by the wall portion 16 is used to fill the tank with the constituents of the plaster, while the portion formed in part by the wall section 17 is the discharge means of the tank.

It will be seen, referring again to Figure 1, that the flared wall 17 forms a chute leading from the tank and in the majority of mixers today this chute is of a width somewhat less than the width of the tank 15 to permit discharge of the mixed plaster into a hod or other container used to carry the plaster to the construction zone where the plaster is to be applied to the wall surface or for holding the plaster until used.

Where the tank is of the configuration just described, the section 11 would be formed of a size and configuration sufficient to close the discharge portion of the opening of the tank. The section 13 would also, of course, be of a size sufficient to close the opposite portion of the opening and which, as described above, is used to normally introduce the constituents of the plaster mix. In any event, the sections 11, 12, and 13 are of such a size and configuration as to completely close the large opening in the tank 15.

In the illustrated embodiment of the present invention, the cover element is mounted to the tank 15 by securing the intermediate section 12 to the tank in such a relative

3

position thereon as to properly position sections 11 and 13 over the filling and discharge portions of the opening. The section 12 in the illustrated embodiment of the invention is held to the tank by mounting threaded studs 18 to the opposite walls of the tank. These studs, referring now to Figure 4, may be conveniently fixed to the walls of the tank by forming spaced apertures in the wall and securing a stud in each aperture by weld, as indicated at 19. The section 12 of the cover element is formed with depending flanges 21 at the opposite ends thereof, which flanges are formed with slots 22 adapted to receive the studs 18.

Once the cover element is mounted to the tank with the studs 18 received within the slots 22, angle members 23, each having an opening through one leg thereof, are mounted to the section 12 with a stud 18 passing through the opening in the one leg thereof and with the other leg engaged over the upper face of the section 12. With the angle members in position on the studs 18 as above described a fastening member such as the wing nuts 24 shown, can be engaged with each stud to tightly clamp the one leg of the angle member 23 against the flange 21 of the section 12. It will thus be seen that this assembly rigidly holds the cover 12 to the tank and yet permits the cover to be demounted from the tank for cleaning purposes.

The section 12 is formed with a relatively large aperture 25 to the defining edges of which are secured, by welding operation, the discharge throat of a hopper 26. The hopper 26 presents a rectangular filler opening 27 and the walls thereof converge downwardly to form the discharge throat at the opening 25 in the section 12. The opposite end walls 28 and 29 of the hopper terminate at the discharge throat in deflected portions 31 and 32 arranged substantially parallel to each other. The wall 33 also terminates in a similar deflected portion although the opposite wall 34 is not formed with such a terminal portion. The purpose of this construction will be hereinafter more fully explained.

The hopper 26 is intended to receive the one end portion of a bag, such as indicated at 35, holding the light weight filler material to be used in the plaster. The bags used by various manufacturers or suppliers are now standardized and the hopper is of such a size relative to this now standardized bag size as to sealingly engage with the end portion of the bag supported by the flaring sides of the hopper. When the bag 35 is placed in the hopper in the position shown in Figure 1, the bag is partially supported by an elongate rod 36 carrying a plurality of cutter elements 37. The rod 36 is rotatably supported by being passed through aligned apertures formed in the wall portions 31 and 32 of the walls 28 and 29, respectively. It will be remembered that these wall portions are substantially parallel to each other and thus permit rotational mounting of the rod 36 merely by the aligned openings formed therein.

In the illustrated embodiment of the present invention, the rotational mounting of the rod is effected by forming the rod with terminal portions circular in cross section with the one terminal portion 38 of a length longer than the opposite portion 39. To mount the rod in the apertures formed in the wall portions 31 and 32 of the hopper the longer terminal portion 38 is inserted through the aperture in the wall portion 32 and the rod longitudinally moved to permit insertion of the shorter terminal portion 39 in the opening of the wall portion 31. After the cylindrical terminal portions are properly mounted in the aligned apertures, some means such as a cotter key is passed through a transverse bore formed in the terminal portion 39 to prevent longitudinal movement of the rod 36 in a direction to bring about disengagement of the terminal portion 39 with the aperture of the wall portion 31.

To operate the bag rupturing means formed by the rod and the cutter elements 37, a handle 41 is fixedly mounted to the terminal portion 38 of the rod. The handle may be grasped by a user and arcuately moved to move the cutter elements 37 through the lower portion of the bag 35 to bring about discharge of the contents of the bag downwardly through the opening of the section 12 of the cover element.

In the form of the hopper illustrated, the rod 36 carrying the cutter elements is mounted to the hopper so that the cutter elements 37, when the handle 41 is swung to the position shown in Figure 1, will engage and be sup-

ported by the wall 33 of the hopper, as clearly shown in Figure 2. It will be seen in this position that gravity will act to hold the cutters 37 against the wall 33 and the handle in the position shown.

Once the bag 35 is positioned in the hopper, the handle 41 may be grasped by the right hand of the user and moved to the right, as viewed in Figure 1, to arcuately move the cutters 37 from their position engaging the wall 33 through the lower end of the bag 35 to bring about the discharge of the contents thereof downwardly into the tank 15.

As above explained, the flared walls of the hopper together with the bag itself form a seal to prevent escape of the material of the bag upwardly of the hopper and all of the contents of the bag will be emptied into the tank 15. It should be understood that in this operation of discharging the contents of the bag the sections 11 and 13 will be in their closed position, as illustrated in Figure 1. With the sections 11 and 13 in this position, the material of the bag will be prevented from escaping through the opening of the tank 15 and the paddle members of the tank can then be operated to bring about the thorough intermixing of the water and other materials forming the plaster mix.

Once the constituents have been thoroughly mixed, the section 11 can be pivotally moved to uncover the discharge chute formed in part by the tapering wall 17 of the tank and the finished plaster discharged through the chute by tilting the tank 15 about the axis of the bearing members 42 which support the tank 15 to the frame of the machine. To permit this tilting of the tank the latter is formed in most machines today with a handle 43 which is welded or otherwise secured to the tank.

To hold the sections 11 and 13 each in a position in which the portions discharge and filling of the tank opening is uncovered, friction latches 44 are mounted to each of the sections 11 and 13 and these latches are adapted to engage over the upper edges of the wall members 33 and 34 of the hopper. In the illustrated embodiment of the invention, each latch comprises a spring-biased finger 45 pivotally mounted through a small bracket 46 to the upper surface of each section. Each finger 45 is provided with a notch 47 adapted to receive the upper edge of the particular wall with which the finger engages.

To produce movement of the fingers 45 as they engage with their respective walls of the hopper, each finger is formed with a cam surface 49 which, in conjunction with the engaged wall of the hopper, acts to urge the finger away from the wall against the action of the spring 48 to permit the finger to move into a position in which the notch 47 receives the upper edge of the wall. The spring 48 now, as should now be understood, will hold the finger down over the engaged wall and prevent movement of the section of the cover element.

To release either one of the latch fingers from the engaged wall it is only necessary to swing the latch finger away from the wall against the action of the spring a distance sufficient to clear the walls of the notch from the engaged wall, after which the cover can be pivotally moved to its position overlying the portion of the opening of the tank which it is intended to cover.

To facilitate discharge of the contents of the bag 35, the device may be formed with a support element 51 comprising a frame removably secured to the hopper 26 which supports, at the upper end thereof, a plate 53 carrying a plurality of sharpened tines 54 adapted to pierce the bag 35 when the latter is thrust against the tines. The tines 54 actually perform two functions in the use of the device, for once the tines have pierced the bag, they tend to hold the bag upright of the hopper 26 and also form means for rupturing the bag to permit air to enter the bag as the contents are discharged therefrom into the tank 15. This prevents the formation of a partial vacuum within the bag which would act to hold the contents against discharge once the cutter elements 37 had been operated to form the openings through which the contents are discharged.

The support 51, as should now be seen, also relieves the workman of the necessity of holding the bag 35 upright in the hopper and once the bag has been thrust against the tines 54, the workman then is free to actuate the cutter elements 37 as above described. It is generally necessary, after the bulk of the bag contents have emptied, to shake the bag slightly to be sure that all of the material held by the bag is emptied into the

tank and the bag, as above explained, is allowed to remain in position within the hopper until after the completion of the mixing operation.

It should be seen now that the device of the present invention provides a means for completely sealing the large opening of the mixing tank of a plaster making machine to obviate the disagreeable condition inherent with the use of light weight filler materials. The device, when mounted to the tank, in no way complicates the use of the tank, for, as above explained, the sections 11 and 13 may be moved into, and held in, a position in which the opening of the tank is exposed to permit filling of the tank with the heavier materials and for discharge of the mixed plaster from the tank.

Although the now preferred embodiments of the present invention have been shown and described herein, it is to be understood that the invention is not to be limited thereto, for it is susceptible to changes in form and detail within the scope of the appended claims.

We claim:

1. A hopper member for closing the filler and discharge opening of the mixing tank of a plaster mixing machine, comprising: a cover element including a median section and pair of sections hingedly mounted to opposite sides thereof; means for attaching said cover element to said tank to close the opening therein, the hingedly mounted sections being movable to open opposite portions of said opening for filling and discharging the tank; a hopper mounted to said median section for discharging material through an opening in said section, said hopper having flared sides adapted to receive the one end portion of a bag containing finely divided material; a plurality of cutters rotatably mounted within said hopper; and means, including manually operable means, for rotating said cutters through the end portion of the bag received by said hopper whereby the contents thereof are discharged into said tank, the flared walls of said hopper sealingly engaging said bag to prevent escape of material upwardly of said hopper and into the atmosphere.

2. A hopper member for closing the filler and discharge opening of the mixing tank of a plaster mixing machine, comprising: a cover element including a median section and a section hingedly mounted to each of the opposite sides thereof; means for attaching said element to said tank to close the opening therein, the hingedly mounted sections being movable to open opposite portions of said opening for filling and discharging the tank; a hopper mounted to said element for discharging material through an opening in said element, said hopper having flared sides adapted to receive the one end portion of a bag containing finely divided material; a plurality of cutters rotatably mounted within said hopper; means for rotating said cutters through the end portion of the bag received by said hopper whereby the contents thereof are discharged into said tank, the flared walls of said hopper sealingly engaging said bag to prevent escape of material upwardly of said hopper and into the atmosphere; and means carried by said hopper to extend thereover for supporting the upper end of said bag.

3. A hopper member for closing the filler and discharge opening of a mixing tank of a plaster mixing machine, comprising: a panel section having an opening therein; means for attaching the opposite ends of said panel to opposing walls of said tank to extend across the opening therein; a second panel section hingedly connected to one margin of said first section; a third panel section hingedly connected to the opposite margin of said first section; a hopper fixed to said first panel section for receiving materials for discharge through the opening in said first section into said tank; a plurality of cutter elements mounted within said hopper adjacent the discharge end thereof for puncturing the wall of a bag containing finely divided material when the lower end of said bag is received within said hopper; and means carried by said hopper for supporting the upper end of said bag in a substantially vertical position relative to said hopper, the wall of said hopper being outwardly flared and coacting with the lower end of said bag to prevent escape of material upwardly of said hopper.

4. A hopper member for closing the filler and discharge opening of a mixing tank of a plaster mixing machine, comprising: a first panel section; means for attaching said section to said tank to extend across a me-

dian portion of the opening therein; a second panel section hingedly connected to one margin of said first section and adapted to cover a marginal portion of said opening; a third panel section hingedly connected to the opposite margin of said first section and adapted to cover the other marginal portion of said opening, said second and third panel sections being independently movable to uncover the said marginal portions of said opening; a hopper fixed to said first section, and having a discharge opening registering with an opening in said first section, for discharging materials into said tank; a plurality of cutter elements mounted within said discharge opening; and means for manually operating said cutter elements for puncturing the wall of a bag containing finely divided material having the one end thereof received within said hopper.

5. A hopper member for closing the filler and discharge opening of the mixing tank of a plaster mixing machine, comprising: a cover element including a mounting section and a section hingedly mounted to each of the opposite sides thereof; means for attaching said element to said tank to close the opening therein, the hingedly mounted sections being movable to open opposite marginal portions of said opening for filling and discharging the tank; means carried by each of said hingedly mounted sections for holding each section in an open position; a hopper mounted to said element for discharging material through an opening in said element, said hopper having flared sides adapted to receive the one end portion of a bag containing finely divided material; means, including manually operated means, for rupturing the end portion of the bag received by said hopper whereby the contents thereof are discharged into said tank, the flared walls of said hopper sealingly engaging said bag to prevent escape of material upwardly of said hopper and into the atmosphere.

6. A hopper member for closing the filler and discharge member of a mixing tank of a plaster mixing machine, comprising: a cover element to be detachably mounted to said tank to extend across and close the opening therein; a hopper fixed to said cover element for receiving a material to be discharged therefrom through an opening of said element into said tank, said hopper having flared sides adapted to receive the one end of a bag containing the material to be introduced into the mixing tank of said machine; cutter means mounted within said hopper adjacent the discharge end thereof for puncturing the wall of said bag whereby the contents thereof are discharged downwardly through the opening in said cover element; a plurality of tines; and means for mounting said tines above said hopper whereby a bag may be urged against said tines to puncture the wall thereof to permit air to enter the bag as the contents thereof are discharged downwardly into the tank through the punctures formed by said cutter elements.

7. A hopper member for closing the filler and discharge member of a mixing tank of a plaster mixing machine, comprising: a cover element to be detachably mounted to said tank to extend across and close the opening therein; a hopper fixed to said cover element for receiving a material to be discharged therefrom through an opening of said element into said tank, said hopper having flared sides adapted to receive the one end of a bag containing the material to be introduced into the mixing tank of said machine; cutter means mounted within said hopper adjacent the discharge end thereof for puncturing the wall of said bag whereby the contents thereof are discharged downwardly through the opening in said cover element, the flared walls of said hopper sealingly engaging said bag to prevent escape of material upwardly of said hopper and into the atmosphere as the material is emptied from the bag; said cover element having sections at opposite sides thereof pivotally movable to uncover opposite marginal portions of the opening of the tank and forming filling and discharging means of the tank.

8. A hopper member for closing the filler and discharge opening of a mixing tank of a plaster mixing machine, comprising: a cover element including a first panel section, a second panel section hingedly connected to one margin of said first section, and a third panel section hingedly connected to the opposite margin of said first section; means for detachably mounting said first section to the tank thereby to mount said cover element to close the opening in said tank; a hopper fixed to

said first section and having a discharge throat registering with an opening in said first panel section; suspension means supported by said hopper for partially supporting a bag in a vertical position with the lower end portion thereof sealingly engaged with the inner surfaces of the walls of said hopper; a plurality of cutter elements mounted within said hopper; means for manually operating said cutter elements for puncturing the wall portion of said bag received within said hopper, whereby finely divided material held by said bag may be discharged into said tank; said suspension means including means for piercing the upper end of said bag for the ingress of air as the material held thereby is discharged.

9. A hopper member for closing the filler and discharge opening of a mixing tank of a plaster mixing machine, comprising: a cover element of a size and shape sufficient to close said opening, said element including a first panel section; a second panel section hingedly connected to one margin of said first section, and a third panel section hingedly connected to the opposite margin of said first section; means for detachably mounting said first section to the tank to extend over a median portion of the opening, said opening being closed by said cover element when the second and third sections thereof are engaged over opposite marginal portions of said opening; a hopper fixed to said first section and having an aperture registering with an opening in said first panel section; means carried by said hopper for partially supporting a bag in a vertical position with the lower end thereof received within said hopper; a plurality of cutter elements mounted within said hopper; and means for manually operating said cutter elements for puncturing the wall portion of said bag received within said hopper, whereby finely divided material held by said bag may be discharged into said tank, said material being held against escape from the tank by said cover element, the walls of said hopper coacting with said bag to prevent escape of the material upwardly of said hopper.

10. A hopper member for closing the filler and discharge member of a mixing tank of a plaster mixing machine comprising: a cover element to be detachably mounted to said tank to extend across and close the opening therein; a hopper fixed to said cover element for receiving a material to be discharged therefrom through an opening of said element into said tank, said hopper having flared sides adapted to receive the one end of a

bag containing the material to be introduced into the mixing tank of said machine; cutter means mounted within said hopper adjacent the discharge end thereof for puncturing the wall of said bag whereby the contents thereof are discharged downwardly through the opening in said cover element, the flared walls of said hopper sealingly engaging said bag to prevent escape of material upwardly of said hopper and into the atmosphere as the material is emptied from the bag; said cover element having pivotally connected sections at opposite sides thereof, the sections being pivotally movable to an elevated position to uncover marginal portions of said opening of the tank; and latch means carried by each of said sections and engageable with the adjacent wall of said hopper for releasably holding the sections in the elevated positions uncovering said marginal portions of said opening.

11. A hopper member for closing the filler and discharge member of a mixing tank of a plaster mixing machine, comprising: a tripartite cover element to be detachably mounted to said tank to extend across and close the opening therein; a hopper fixed to the median part of said cover element for receiving materials and discharging the same through an opening of said median part into said tank, said hopper having flared sides adapted to receive the one end of a bag containing a material to be introduced into the mixing tank of said machine; cutter means mounted within said hopper adjacent the discharge end thereof for puncturing the wall of said bag whereby the contents thereof are discharged downwardly through the opening in said cover element; a frame means carried by and extending upwardly of said hopper; a plurality of tines; and means for mounting said tines to said frame means above said hopper whereby a bag may be urged against said tines to puncture the wall thereof to permit air to enter the bag as the contents thereof are discharged downwardly into the tank through the punctures formed by said cutter elements, said tines passed through said bag partially supporting said bag and holding the same upright relative to said hopper; at least one end part of said cover element being pivotally movable to uncover a portion of said tank opening for discharging finished plaster therethrough.
